VEHICLE SIDE WALL CONSTRUCTION

Frank L. Murphy and James E. Candin, Jr., Chicago, Ill., assignors to Pullman-Standard Car Manufacturing Company, Chicago, Ill., a corporation of Delaware

Application August 9, 1944, Serial No. 548,682

4 Claims. (Cl. 105—401)

1

The invention relates to vehicle wall construction having girder sides including vertical and longitudinal framing members on the inner faces thereof and auxiliary members mounted upon the outer faces of the girder walls for detachably securing separate exterior sheathing assemblies fixedly to said girders.

The principal object of the invention is to provide outer sheathing for girder type cars with means fixedly securing the sheathing to the girder without penetrating the girder wall by the fastening devices, such means functioning also to detachably support the sheathing members.

An important object is to provide sheathing supporting members disposed vertically at spaced intervals along the outer face of a girder wall and interconnected in functional relationship by stiffening members welded to the inner face of the girder wall and extending longitudinally thereof effectively to supplement each other to rigidify the girder wall.

A further object is to provide an outer sheathing assembly adapted for application to girder side walls of new or existing equipment of welded or riveted construction for the purpose of enhancing the appearance of the car exterior.

The foregoing and other objects and advantages of the invention will appear from the following description taken in connection with the accompanying drawings, in which:

Fig. 1 is a side elevational view of a railway vehicle embodying the side wall sheathing arrangement of the invention and showing the disposition of the sheathing members above and below the windows for the full length of the vehicle;

Fig. 2 is an enlarged fragmentary side elevational view of the vehicle showing the location of the sheathing supporting verticals welded to the outer face of the girder wall and disposition thereof with respect to location of the windows and longitudinal and vertical framing members secured to the inner face of the girder side;

Fig. 3 is a vertical cross sectional view taken on line 3—3, of Fig. 2, thru vehicle side above the windows, showing the girder wall with sheathing supporting verticals secured to the outer face thereof and the sheathing assembly secured thereto, and also the location of the longitudinal stiffening member welded to the inner face of the girder intermediate the side plate and window header longitudinals;

Figs. 4 and 5 are views similar to Fig. 3, taken on lines 4—4 and 5—5, of Fig. 2, showing in larger detail the method of welding the vertical sheathing supporting members to the outer face of the

2

girder at the side plate and window header positions, respectively, and means for detachably securing the sheathing to the verticals and the moulding sections to the girder at points beyond the ends of said verticals;

Fig. 6 is a view similar to Fig. 3, taken on line 6—6, of Fig. 2, thru vehicle side below the windows, showing the girder wall with sheathing supporting verticals secured to the outer face thereof and the sheathing assembly secured thereto, and also the location of the longitudinal stiffening member welded to the inner face of the girder intermediate the belt rail and side sill longitudinals;

15 Figs. 7 and 8 are views similar to Fig. 6, taken on lines 7—7 and 8—8, of Fig. 2, showing in larger detail the method of welding the vertical sheathing supporting members to the outer face of the girder at the belt rail and side sill positions, respectively, and means for detachably securing the sheathing to the verticals and the moulding sections to the girder at points beyond the ends of said verticals; and

25 Fig. 9 is a horizontal sectional view taken on line 9—9, of Fig. 6, showing the channel shaped vertical sheathing supporting members welded at their flanges to the girder side with their webs spaced from the girder side and perforated to receive fastening devices for detachably securing the sheathing members to the wall in spaced relation to the girder plate, and showing also the insulating tape between sheathing and verticals.

20 In said drawings, the invention is indicated by the application of the sheathing to a railway car 10 as shown in all the figures. The sheathing 11, in Fig. 1, extends preferably the full

length of the car, above and below the windows 12, continuously or in sections, as may be found most expedient. The depending apron portion

30 13 at the car side, between the trucks 14, may likewise be fitted with sheathing members adapted for application to the apron framing

35 15, as shown in Figs. 1 and 6. The side framing members, including girder sheet 16, may be of

40 high strength steel and the sheathing 11 preferably of stainless steel; the framing side posts

45 17 extend upwardly in pairs between the windows 12 from the longitudinal side sills 18 to the side plate longitudinals 19, as best shown

50 in Fig. 2. Immediately above the windows and disposed longitudinally between the posts 17 ad-

jacent the ends of respective windows 12, are

55 window header members 20, preferably welded to the inner face of the girder sheet 16, as at

21 in Fig. 5, and supplemental longitudinals 22

beneath said headers for attachment of window sash frames, not shown, secured to the girder by welding, as at 23 in this figure.

Below the windows 12, belt rail longitudinals 24 are secured to the girder sheet 16, preferably by welding, and extend from post to post at adjacent ends of respective windows 12, as best shown in Fig. 2, and carrying auxiliary longitudinals 25 for attachment of adjacent window sash frames.

Connecting each pair of posts 17 between adjacent windows 12 and the girder sheets 16 above and below the windows, are the pier panels 26, to the inner faces of which are secured, in addition to said posts, header extension pieces 27, belt rail extension members 28, and intermediate thereof the reinforcement elements 29 to stiffen the panel between the windows, all as shown in Fig. 2.

To the outer side of the vehicle wall above described is to be detachably secured a sheathing assembly of stainless steel, or metal having like surface characteristics, in a manner to avoid penetration of girder sheet 16 by screws or other fastening devices for supporting the sheathing. For this purpose vertical supporting members 30 and 32 are disposed, respectively, above and below pier panels 26 and intermediate the framing posts 17, and other vertical members 31 and 33 for supporting sheathing members above and below the windows, respectively, and secured by welds 34 to the outer face of the girder sheet, as best shown in Figs. 2, 4, 5, 7, 8 and 9. The supporting members are preferably channel shape as indicated in Fig. 9 and applied with their flanges 35 directed inwardly for attachment to the girder by welding 34 as shown, with the web 36 connecting the flanges spaced outwardly from the face of the girder sheet 16 to permit application of screws 37 tapped into the web for detachably securing the sheathing to the wall as depicted in this figure. The channel form of these supports renders them suitable for wall stiffening purposes when fixedly secured to the girder sheet by welds 34 intermittently applied at the flanges 35 and since the supports are respectively of a length to overlap the longitudinal framing members 18 and 24 below the windows and 19 and 20 above the windows, they serve effectively to rigidify the girder sheet. Between each of said supports and the sheathing may be interposed a fibrous insulating cushion 38 adhesively applied to the webs 36 of the supports to prevent vibration of metal to metal contact. In the areas above the several windows 12, the girder sheets are reenforced by longitudinal members 39 welded to the girder at a point intermediate the side plate longitudinals 19 and headers 20 and between framing posts 17, extending for a substantial distance upon opposite sides of the transverse center of the car and operating to transmit imposed compressive loads to the framing, said members being disposed in intersecting relationship with and functionally to complement the adjacent vertical members 30 and 31 for mutually stiffening the girder sheet.

Beneath the several windows the girder sheets 16 are reenforced by members 40 welded to the girder at a point intermediate the belt rail 24 and side sill 18 and extending longitudinally between adjacent framing posts 17 for substantially full length of the car in intersecting relationship with and to supplement respectively adjacent verticals 33 in stiffening the girder sheet. That portion of the girder sheet between side

posts 17 and beneath pier panels 26 is stiffened by the application of verticals 32 welded to the outer face of the girder to stabilize the girder under stress of car movement.

With the vertical members 30 thru 33 fixed to the girder wall 16 and disposed as above described, above and below the windows and above and below the pier panels 26, the weight of the sheathing members carried by them will be distributed generally thruout the girder wall in areas rigidified by said verticals and stiffening longitudinals secured to the inner face of the girder in complementary relationship with said verticals. As shown in the drawings, the sheathing includes the intermediate members designated 11, and the marginal trim moulding sections 6, 7, 8 and 9 at the side plate, window headers, belt rail, and side sill respectively. The members 11 are preferably corrugated and so proportioned that their valley portions 50 will bear against the insulating tape 38 at respective vertical supporting members with sufficient pressure to prevent vibration; when size permits they are formed with intermediate channeled portions 51 having attaching base web portions 52 and convergent side walls 53 defining a groove having an elongated opening 54 of less width than said base 52 and adapted to receive a moulding insert 55 having resilient side walls 56 conforming to slope of groove walls 53 and movable towards each other when insert is pressed thru the groove opening, then away from each other to assume their normal expanded position for retention within the groove under pressure of the expanded side walls 56 against adjacent side walls 53, of the respective grooves. At their edges the sections are formed with base flanges 57 and inclined side wall portions 58 designed to complement like portions on associated sections to form therewith grooves 59 with the base flanges 57 in overlapping relationship for connection with adjacent vertical members, said grooves being covered by insert mouldings 60 having the characteristics of inserts 55 for the intermediate channels 51.

Incorporated in the sheathing assembly in the embodiment disclosed, is an eaves moulding of heavier gauge material than associated sections of the sheathing and of modified Z configuration extending the length of the car and secured to the structure thru upright flange 5 between roof sheet 4 and girder plate 16 and side plate 19 by rivets 3 and having an outwardly and downwardly sloping web portion 61 with depending lip flange 62 spaced outwardly from the car side to function as a water shed. The sheathing assembly includes also a marginal trim moulding section 6 formed to have interlocking relationship with the eaves moulding along its upper edge and lap-over connection with underlying section at its lower edge. Like the associated members of the assembly, the trim moulding 6 is corrugated with valleys 50 bearing against insulating tape 38 on adjacent vertical members and terminating in groove wall portion 63 and base flange portion 64 at the lower edge of the section designed to complement similar wall and flange portions on adjacent underlying section to form groove 59 to receive securing devices 37 for attachment to adjacent verticals 31, after which moulding piece 60 may be inserted to conceal the securing means, as shown in Figs. 3 and 4; the upper edge of the section is shaped to conform to overlying eaves moulding with an outwardly projecting flange portion 65 downwardly inclined and terminating in depending edge flange 66.

adapted for interlocking relationship with contiguous web and lip, respectively, of the eaves moulding and held nested therewith under pressure exerted by the resiliency inherent in the metal of the trim moulding 6 proportioned to prevent vibration between the sections.

The trim mouldings 7 at longitudinals 22 above the windows and mouldings 8 at the belt rail 24 below the windows are of like configuration and formed with one edge angle shaped to provide base flange 67 adapted for lap-over connection with corresponding flange 57 on associate section, and a side wall portion 68 extending outwardly at an acute angle to the base flange and serving to complement a like wall portion 58 on adjacent section to form groove 59 adapted to receive insert moulding 60 to complete the finish for the sheathing at these positions. These mouldings 7 and 8 are formed along their opposite edges with rebent portions providing a bearing ridge 70 for engaging the girder sheet and marginal hook flanges 71 for resiliently engaging complementary flanges 72 on retaining strips 73 having attaching flanges 74 for securing them to the girder sheet, preferably by welding as at 75, the mouldings being so proportioned as to insure interlocking engagement between moulding flange 71 and retainer flange 72 and positive bearing of moulding ridge 70 upon the girder wall 16 when secured to sheathing supporting vertical members by the fastening devices 37 thru lap-over base flange 67, as best shown in Figs. 4 thru 7.

The sheathing assembly is completed by the application of trim moulding member 9 at the side sill position as shown in Figs. 6 and 8. The member is corrugated with valley portion 50 bearing against adjacent supporting vertical member 33 and with its upper edge formed to provide base flange 77 adapted for lap-over connection with corresponding flange 57 on adjacent overlying section, and a side wall portion 78 extending outwardly in acute angle relationship with the base flange and functioning to complement a companion wall portion 58 on the associate member 11 to form groove 59 adapted to receive insert moulding 60 to complete the finish for the assembly at this position. At its lower margin, the section is formed with a rearwardly projecting flange portion 76 extending beyond the plane of girder 16 for attachment to side sill 18 which may be by the same fastening devices 79 used to secure apron supporting hinge brackets 80 to the sill, as shown in Fig. 6.

As shown in Figs. 1 and 3, suitable provision is made for the application of a name plate 2 to the sheathing above the windows. The plate may be attached to the wall in any approved fashion, preferably by securing devices extending thru insert mouldings 55 and 60 and a fixed part on the girder sheet to prevent separation of the plate from the sheathing.

In practice, it is contemplated that sections 11 of the sheathing between respective trim moulding sections 6 and 7 above the windows, and 8 and 9 below the windows, will first be joined together by welding in overlapping relation the base flanges 57 of adjacent sections, then applying the connected sections to the girder as a unit thru medium of the vertical supporting members to which the sheathing is detachably secured by fastening devices 37 at said overlapping flanges. With the sheathing above the windows thus positioned, trim moulding sections 6 and 7 are then interlocked with fixed components on the car, at

points beyond the ends of the vertical members, with their respective base flanges 64 and 67 overlapping corresponding flanges 57 on adjacent sections 11 with which and the verticals they are connected by fastening devices 37. In similar fashion, with the sheathing below the windows in position, trim mouldings 8 and 9 are secured to the car with their respective base flanges 67 and 77 overlapping corresponding flanges 57 on adjacent sections 11 to which and adjacent vertical members they are connected by fastening devices 37, and when the insert mouldings 55 and 60 are entered in grooves 51 and 59, respectively, the finish for the installation is complete.

It is conceivable that changes in the width of intermediate sections 11 may be made to conform to variations in height of car side above and below the windows or between the trim mouldings above and below the windows, so that a greater or lesser number of sections would be required to cover the wall area, and they may be made with or without the intermediate groove 51 having single web attaching base 52, depending upon the width of the particular section.

When fixed to the car side as shown, the sheathing assembly supporting members function to supplement associated stiffening and framing members to rigidify the girder wall. As will be understood from the construction hereinbefore outlined, the sheathing may be applied from the outside without disturbing the interior finish and permits of the ready removal and replacement of damaged sections. The sheathing thus applied is corrosion resistant, easy to clean, and protects the girder wall from exposure to the elements, and maintainable in proper operating condition at a minimum of labor and expense.

What is claimed is:

1. In vehicle side wall construction including an imperforate girder sheet, vertical and horizontal framing members welded to the inner face of said girder sheet, window openings in said girder sheet between certain of said framing members, vertical rigidifying members welded to the outer face of said girder sheet in areas between said vertical framing members and of a length to overlap said horizontal framing members, said rigidifying members being disposed in substantial alignment above and below the window openings, and sheathing elements detachably secured to the rigidifying members by means spaced from said girder sheet and leaving the girder sheet imperforate.
2. In vehicle side wall construction including a substantially continuous girder sheet, vertical and horizontal framing members welded to the inner face of said girder sheet, window openings in said girder sheet between certain of said framing members, vertical rigidifying members welded to the outer face of said girder sheet in areas between said vertical framing members and of a length to overlap said horizontal framing members, said rigidifying members being disposed in spaced relation above and below the window openings, and horizontally disposed substantially continuous sheathing elements, above and below the window openings detachably secured to the rigidifying members by means spaced from said girder sheet and leaving the girder sheet imperforate.
3. In vehicle side wall construction including an imperforate girder sheet, vertical and horizontal framing members welded to the inner face of said girder sheet, window openings in the

7
girder sheet between certain of said framing members, rigidifying members of channel section welded to the outer face of said girder sheet with their flanges directed inwardly in edgewise engagement with the girder sheet and their connecting web portions spaced outwardly from the girder sheet, said rigidifying members extending vertically in areas between said vertical framing members of a length to overlap said horizontal framing members above and below the window openings respectively, and horizontally disposed sheathing assemblies above and below the window openings detachably secured to said web portions in spaced relation to said girder sheet whereby to leave the girder sheet imperforate.

4. In vehicle side wall construction including an imperforate girder sheet, window openings in the girder sheet, longitudinal side plate and window header framing members secured to the inner face of said girder sheet above said window openings, longitudinal belt rail and side sill framing members secured to the inner face of the girder sheet below the window openings, vertical framing posts secured to the inner face of the girder sheet at opposite sides of the window openings, rigidifying members of channel section welded to the outer face of said girder sheet with their flanges in edgewise engagement with the girder sheet and their connecting web portions spaced outwardly from the girder sheet, said rigidifying members being disposed in spaced

8
relation above and below said window openings in areas between said vertical framing posts and extending vertically in overlapping relationship with said longitudinal framing members, and outer sheathing assemblies above and below the window openings detachably secured to the web portions of said rigidifying members in spaced relation to said girder sheet whereby to leave the girder sheet imperforate.
